UNITED STATES PATENT OFFICE.

LEON H. BEAN, OF NEW YORK, N. Y., ASSIGNOR TO HOLLANDER-LANGEE, INC., A CORPORATION OF NEW YORK.

MACHINE FOR MAKING BUTTONS.

Application filed August 3, 1922. Serial No. 579,317.

Broadly considered, my present invention relates to machines for operating upon blanks and more particularly for simultaneously operating upon a plurality of blanks for producing predeterminedly shaped articles in predetermined timed relationship.

While my present invention has a wide range of usefulness, inasmuch as it finds a peculiar field of utility as an efficient apparatus for the rapid manufacture of buttons from materials such as horn, I will proceed to describe the invention as it is utilized in connection with a continuous process such as is employed for the quality production of buttons.

As will be understood as the description proceeds the objects operated on are preferably in the form of blanks and of a material which can be molded in its broadest aspects. My invention comprises the shaping of the blank by pressure and in the preferred practice, heat is first applied to the blank so as to render it readily moldable under pressure, and the pressure is then applied so that the blank will begin to lose its heat during the application of pressure and will have cooled substantially upon the completion of such step which cooling will be materially assisted by the contact of the blank with pressure applying instrumentalities.

I have found that due to the fact that the pressure must be continued for an appreciable time so as to permit of the proper forming of the button and of the necessary cooling, the production per machine is small, and the result and cost of production high.

Among the more important objects of my invention therefore, are; the provision of a machine for operating simultaneously upon a plurality of blanks in timed relationship; the provision of a machine so arranged and constructed that while one portion thereof is operating upon a blank, another portion thereof is in inoperative position; the provision of a machine for operating upon a plurality of blanks in cycles; the provision of a machine for operating upon a plurality of blanks simultaneously, so arranged and constructed that different portions of the machine bear different timed relationships with reference to each other and with reference to the blanks; and the provision generally of a new and improved and sim-

plified machine for manufacturing buttons.

For the attainment of these objects and such other objects as may appear to be pointed out hereinafter, I have illustrated one embodiment of my invention in the appended drawing wherein—

Figure 1 is a front elevational view of the machine, partly broken away;

Figure 2 is a section taken on line 2—2 of Figure 1; and

Figure 3 is a section taken on line 3—3 of Figure 1.

Upon viewing Figure 1 it will be observed that in the embodiment of my invention illustrated in the drawings, the table or platform 10 of the machine is provided upon its upper surface with the die portions 11 in which are received the blanks 12 from which the button is to be formed or shaped, these die portions 11 forming the lower surface of the buttons. As will be observed, the platform is arranged to support simultaneously six blanks, it being of course, understood that this number may be varied, it being shown merely for purpose of illustration. The blanks 12 are operated upon by the press plungers 13, one press plunger being provided for each blank holding a die portion 11 carried by the platform 10. These press plungers 13 are provided with the die portions 14 on the lower surface to form the upper face of the button and are further provided with the pins 15 adapted to form any desired number of perforations such as are generally found in buttons of this character. As will be understood the employment of die surfaces of any particular character is not essential nor is the use of the hole punches 15.

The plungers 13 are supported in any desired or preferred manner for reciprocation, and are illustrated slidably supported in the member 16 carried by the side supports 17 of the machine at a predetermined distance above the platform 10. Each press plunger 13 is provided at its upper end with a roller 18, arranged to rotate freely within the cut out portion 19 provided at such upper end of each of the press plungers.

As will be further observed upon viewing the various figures of the drawings, an upper cam shaft 20 is supported for rotation in a position preferably directly above

the press plungers 13, this cam shaft 20 having affixed thereto a plurality of cams 21, one for each of the six press plungers, six cams therefore being illustrated in the drawing, a cam being positioned above each press plunger. Each of these cams 21 has its perimeter 22 made concentric with the axis of rotation of the shaft 20 for substantially 300 degrees, the cam member 21 being 5 cut away for substantially 60 degrees of its perimeter to form the depression or cut out 23.

In affixing these cams 21 to the cam shaft 20 they are arranged in staggered positions 15 so that the cut away portion 23 of each of the cams 21 is angularly offset from that of all the other cams. This is preferably done as can be observed upon viewing Figures 2 and 3 by arranging each cut out 23 at an 20 angle of 60 degrees from that of these on each side thereof.

The cam shaft 20 is driven by gear 25 which is affixed thereto, which in turn is 25 driven by a gear 26 upon the main drive shaft, the gear 26 driving the gear 25 at a ratio of one to six. The gear 26 in turn is arranged to be driven from the pulley 27 by means of a clutch 28 controlled by the 30 clutch lever 29, operated through the rod 30 by the treadle 31 and as illustrated is of a type so as to give the gear 26 one revolution upon each operation of the treadle 31, and at the end of such one revolution the clutch 28 is automatically thrown out in 35 a manner that is well known in this art.

From the description thus far given it will be understood that when the treadle 31 is operated the clutch 28 is engaged to give the gear 26 one revolution upon which the 40 gear 25, and with it the cam shaft 20 is given one sixth of a revolution, in a manner and for purposes that will shortly be pointed out.

A gear 30' of the same size as the gear 45 25 is in mesh with the gear 25 and in turn carries a lower cam shaft 31' upon which are carried a plurality of specially arranged cam members 32 therefor shown, a cam being positioned opposite each press plunger. 50 Supported upon the machine and adjacent to each press plunger are a plurality of bell crank levers 33 loosely pivoted to the frame at 34, one end of each bell crank lever projecting into a slot 35 formed in each plunger and in which slot such end is loosely pivoted. The other end 36 of the bell crank lever 33 is provided with a roller 37 arranged to be 55 engaged by the adjacent cam member 32 when said cam member is moved past the roller.

The cams 32 are also preferably arranged in staggered relation each cam being positioned angularly 60 degrees removed from the adjacent cams. It will be further understood that the cams 32 and the cut away

portions 23 are so positioned relatively that when a cut away portion 23 of a cam 21 is directly opposite the roller 18 of its co-acting press plunger 13, the cam member 32 which co-acts with the same press plunger 70 will be moved by contact with the roller 37 to cause the bell crank 33 to move about its pivot 34 and thus move the press plunger upwardly so as to cause the roller 18 to engage in the cut away portion 23 of the cam 75 21 immediately thereabove.

As will be observed upon viewing Figure 1, after each operation of the treadle the machine will be somewhat as shown in Figure 1 with five of the plungers down and 80 one up. Assuming, therefore, the machine in the position of Figure 1, the operation of the treadle of Figure 1 will cause a single revolution of the gear 26 which, in turn, will cause one-sixth of a revolution of the upper 85 cam shaft 20 and a similar one-sixth of a revolution of the lower cam shaft 31'.

This single operation of a treadle will therefore cause each of the cams 21 to move angularly for 60 degrees thus moving that 90 cam 21 which appears on the extreme left of Figure 1 to a position where the concentric portion 22 of the cam 21 is brought into engagement with the wheel 18 of the plunger 13 to force said plunger down into 95 contact with a blank which has been in the meanwhile positioned therebeneath.

While this shift of the mechanism on the extreme left is taking place, it will be understood from the description thus far given 100 that the movement of four of the cams will produce no change except to bring a new portion of the concentric surface 22 of each into engagement with its contacting roller without, however, permitting or causing any 105 change in the position of the roller 18 or of the plunger 13 which carries said roller.

The sixth and remaining cam 21 will, however, upon said movement angularly for 60 degrees, be caused to bring into co-action 110 with its opposed or co-acting roller 18 the depressed portion 23 thereon thus permitting the plunger 13 to rise and to press the roller carried by it in this cut-out portion 23.

While this movement of the cams of the 115 upper cam shaft is being effected with the results pointed out, the different cams 32 of the lower cam shaft 31' each has been similarly moved, so that when the concentric portion of one cam 21 is brought into contact with its co-acting roller 18 the cam 32 which co-acts with the plunger which carries said roller is moved out of the path of the bell crank lever which also forms part of the associated mechanism for operating one 120 of the plungers and similarly when the depressed portion 23 of any cam 21 is brought into opposition with a roller 18 the cam 32 which forms part of the mechanism for this portion will be caused to contact with the 125

roller 37 carried by one end of the bell crank 33 to raise that plunger and hold it in this raised position. It will, of course be understood that the movement of this particular cam 32 is brought to an end while the cam is still in operative contact with the roller 37 so that there is always one cam 32 which acts to maintain a plunger 13 in its raised position.

10 It will be understood that there is but one cam 32 and one cut-away portion 23 for each plunger 13 and that this cam and cut-away portion which co-operate with the same plunger are so constructed and moved as to permit the roller 18 to move into the cut-away portion 23 as the plunger 13 which carries the roller is moved upwardly by its cam 32 through the bell crank lever 33.

What I claim is:

20 1. In a machine for shaping articles in which each article requires the consumption of a relatively long predetermined period of time for the completion of its shaping, a plurality of forming or shaping members, one for each article, and means for operating the same successively in timed relation without a waiting interval of time therebetween, and with each member stationary and active on the article for said relatively long predetermined period.

2. In a machine for shaping articles in which each article requires the consumption of a relatively long predetermined period of time for its shaping, a plurality of forming or shaping members, one for each article, the said plurality of members being selected of a number such that the same may be operated successively in timed relationship without a waiting interval of time therebetween, and with each active on an article for the said relatively long predetermined period.

3. In a machine for shaping articles in which each article is first heated and then shaped and cooled, each article requiring the consumption of a relatively long predetermined period of time for shaping and cooling, a plurality of shaping and cooling members, one for each article, the said plurality of members being selected of a number such that the same may be operated successively in timed relationship without a waiting interval of time therebetween, and with each active on an article for the said relatively long predetermined period.

4. In a machine for shaping articles in which each article requires the consumption of a relatively long predetermined period of time for the completion of its shaping, a plurality of forming or shaping members, one for each article, and means for operating the same successively in timed relation without a waiting interval of time therebetween, and with each member stationary and active on the article for said predetermined period and means for moving each member to inopera-

tive position and out of contact with the article at the end of such relatively long predetermined period.

5. A machine for shaping articles comprising a plurality of shaping members including die members removable into and out of operative position, means for bringing the same into operative position in successively timed relation comprising a rotatable shaft and a plurality of cams operated thereby and angularly positioned with reference to each other, a main shaft and means for operating said first shaft to cause one of the cams to move one of the die elements into operative position upon each revolution of said main shaft.

6. In a machine for molding buttons from blanks, in which each button requires the consumption of a relatively long predetermined period of time for the completion of its shaping, a plurality of button-forming members, one for each blank, the said plurality of members being selected of a number such that the same may be operated successively in timed relation without a waiting interval of time therebetween, and with each active on a button for the said relatively long predetermined period.

7. In a machine for molding buttons from blanks, in which each button requires the consumption of a relatively long predetermined period of time for its shaping, a plurality of female die members adapted to receive the blanks fed thereto, a plurality of male die members cooperable therewith, and means for operating the same successively in timed relation without a waiting interval of time therebetween, and with each stationary and active on a button for the said relatively long predetermined period.

8. A machine for shaping articles, comprising a plurality of shaping members including die elements movable into and out of operative position, means for moving the same into operative position in successively timed relation, and provisions for moving the same out of operative position, the said means and provisions comprising a plurality of sets of cam elements, each set including a plurality of cams angularly arranged relatively to the die elements to operate upon the same successively.

9. A machine for shaping articles comprising a plurality of shaping members including female die elements and male die elements movable successively into cooperative relation with the female die elements, a cam shaft, a plurality of angularly spaced cams thereon, one for each male die element, and operative to move the same into operative position relative to its complementary female die element, a second cam shaft, and a plurality of angularly spaced cams thereon, cooperating with the first mentioned cams and with the male die elements to

move the latter out of said operative position.

10. A machine for shaping articles comprising a plurality of shaping members including movable plunger elements and operating means therefor, including a shaft, a plurality of plunger actuating devices connected thereto, and means whereby a single revolution of the shaft will produce an operation of one of said plunger elements.

11. A machine for shaping articles comprising a plurality of shaping members and operating means therefor, including a shaft,

a plurality of cam elements angularly arranged thereon, and operative in a single revolution of the said shaft for actuating all of the shaping members into operative position, a second shaft operatively connected to said first mentioned shaft, and means whereby a single revolution of said second shaft moves one of said shaping members to operative position.

In testimony whereof I have hereunto signed my name.

LEON H. BEAN.
